[57] ABSTRACT

A magnetic clock comprises an inner revolvable magnetic member and an outer revolvable magnetic member, each being of generally hour glassed shaped and

being arranged concentrically with respect to each other. An hour glassed shaped bearing is positioned concentrically between and exerts a repulsive force on the inner and outer members. The inner and outer revolvable magnetic members each have a plurality of circumferentially spaced apart peripheral elements integrally formed therewith which project radially outwardly therefrom. The outer revolvable member has a minute hand secured thereto for movement therewith and the inner revolvable member has an hour hand secured thereto for rotation therewith. An electro-magnet is positioned adjacent the periphery of the outer member and when energized causes the outer magnetic member to rotate through a predetermined arc of approximately 30°. An electrical pulse mechanism is connected to the electro-magnet and is operable to momentarily energize the electro-magnet which causes movement of the minute hand through the arc which corresponds to a 5 minute increment. The outer revolvable member is also provided with shiftable locking lugs which are shifted for engagement with the inner revolvable member when the outer revolvable member has revolved through an arc of 360°. With this arrangement, the inner revolvable member rotates with the outer member through an arc of 30° and this corresponds to the normal hour hand movement. Suitable magnetic holding means are provided for holding the inner and outer member against movement while the electro-magnet is in an unenergized condition.

MAGNETIC CLOCK

BRIEF SUMMARY OF THE INVENTION

The object of this invention is to provide a novel magnetic clock in which the only moving part comprises a pair of revolvable inner and outer magnetic members, one of which carries the minute hand and the other of which carries the hour hand. A concentrically arranged magnetic bearing member is interposed between and exerts a repulsive force on the inner and outer magnetic members thereby eliminating any wear with respect to the two movable parts.

The revolvable magnetic member which carries the minute hand is revolvable through an arc of approximately 30° which movement corresponds to the movement of the minute hand on a watch after the lapse of 5 minutes.

An electro-magnet positioned adjacent the periphery of the outer revolvable magnetic member carrying the minute hand is momentarily energized by an electrical impulse produced by a pulse generating mechanism. The electro-magnet is energized at 5 minute intervals and suitable holding magnets hold the magnetic member carrying the minute hand against movement during the period when the electro-magnet is in a non-energized condition.

The revolvable magnetic member carrying the hour hand remains stationary until the magnetic member carrying the minute hand has been revolved through an arc of 360° which corresponds to the lapse of 1 hour. When this occurs suitable locking lugs on the magnetic member carrying the minute hand are shifted into engagement with the other magnetic member to rotate the latter through the 30° arc so that it points to the next adjacent hour number. Suitable holding magnets are also provided and are effective for holding the magnetic member carrying the hour hand against movement until the magnetic member carrying the minute hand has been revolved through an arc of 360° .

With this arrangement, an inexpensive highly effective clock is provided and the components thereof are subject to substantially no wear.

BRIEF DESCRIPTION OF THE DRAWINGS

FIG. 1 is a front elevational view of the clock.

FIG. 2 is a rear elevational view of the clock with the back cover removed.

FIG. 3 is a cross sectional view taken approximately along line 3-3 of FIG. 2 and looking in the direction of the arrows, and;

FIG. 4 is a diagrammatic view of the circuit of the clock.

DETAILED DESCRIPTION

Referring now to the drawings it will be seen that one embodiment of the novel clock, designated generally by the reference numeral 10 is thereshown. The clock 10 includes a housing 11 which may be of any suitable design including a peripheral wall 12, a back cover 13 and a front face or dial 14. A transparent front cover 15 covers and protects the face or dial 14 and an inner supporting wall 13a is positioned between the front face and back cover. The dial 14 has suitable hour indicia or numbers 16 arranged circumferentially therearound in a well known manner and the dial is also provided with a minute hand 17 and a hour hand 18 which are movable relative to the dial.

Referring now to FIGS. 2 and 3 it will be seen that the clock includes an outer magnetic member 19 which is of generally hour glass configuration including a front or upper frustro-conical portion 20 and a rear or lower frustro-conical portion 21. The upper and lower frustro-conical portions join each other at a waist 22 and it is pointed out that the outer magnetic member 19 is of circular cross sectional configuration.

An inner magnetic member 23 is positioned concentrically within the outer magnetic member 19 and this inner magnetic member is also of hour glass configuration. The inner magnetic member includes a front or upper frustro-conical portion 24 and a rear or lower frustro-conical portion 25. The upper and lower frustro-conical portions join each other at a waist 26. A generally hour glass shaped stationary bearing 27 is positioned concentrically between the inner and outer magnetic members and the bearing also includes a front or upper frustro-conical portion 28 and a rear or lower frustro-conical portion 29. The frustro-conical portions of the bearing join each other at a waist 30.

The inner and outer magnetic members and the bearing are magnetized while rotating at a high speed to eliminate crowning fields. When so magnetized, under controlled conditions, the polarity of the stationary bearing is arranged with respect to the inner and outer magnetic members so that each exert a repulsive force on each other. Because of the hour glass configuration, these respective members are centered or stabilized both radially and axially. It should be pointed out that each of the inner and outer magnetic members and the bearing have their upper and lower frustro-conical portion formed separately and are thereafter assembled.

Referring again to FIGS. 2 and 3, it will be seen that the outer magnetic member 19 has a plurality of circumferentially spaced apart peripheral elements 31 integrally formed with the lower end 32 thereof and projecting radially outwardly therefrom. It will be noted that in the embodiments shown, the lower end 32 actually defines a flat annular surface and the peripheral elements 31 are disposed in co-planar relation therewith.

The inner magnetic member 23 is also provided with a plurality of circumferentially spaced apart peripheral elements 33 which are integrally formed with lower end 34 thereof and which project outwardly therefrom. It will be noted that it is the upper ends of the inner and outer magnetic members to which the minute and hour hands are affixed. It will further be noted that the peripheral elements 31 are positioned axially below the peripheral elements 33.

A pair of holding magnets 35 are provided and are mounted by suitable brackets 36 on the housing 11 of the clock. It will be noted that the holding magnets 35 are disposed closely adjacent the outer end of the peripheral elements 33 of the inner magnetic member 23. The holding magnets 35 are positioned so that the polarity of the inwardly projecting end is opposite to the polarity of the outwardly projecting peripheral elements 33. Thus these holding magnets will tend to hold the inner magnetic member in a predetermined position until it is forcibly revolved to a new position.

A holding magnet 37 is positioned closely adjacent the outer peripheral edge of the outer magnetic member 19 defined by the peripheral elements 31 and it will be noted that the holding magnet 37 is positioned to exert an attractive force with respect to the peripheral elements 31. An electro-magnet 38 is mounted in the

housing 11 and is disposed in opposed relation with respect to the holding magnet 37. The electro-magnet 38 may be of horse shoe configuration and includes a trip coil 39 with the poles 40 being disposed in spaced apart substantially parallel relation with respect to each other, and being positioned closely adjacent but spaced from the periphery of the outer magnetic member. Electrical conductors 41 and 42 connect the trip coil with a pulse device 43.

The pulse device 43 is positioned within the housing 11 and in the embodiment shown the conductors 41 and 42 are connected to a suitable source of electrical current such as the battery 44. An electrical conductor 45 is connected serially to the electrical conductor 41 and to one contact of a variable resistor or a potentiometer 47. The potentiometer 47 is connected serially to a time constant condenser 48.

An electrical conductor 46 is connected to the conductor 42 and is connected to one contact of a second variable resistor or potentiometer 49 which in turn is connected serially to a field effect transistor 50. The condenser 48 is connected to one contact of a double pole double throw switch 51, and another contact of the switch 51 is connected to the field effect transistor 50. The other contact of the switch 51 is connected to the potentiometer 47. An electrical conductor 52 connects the field effect transistor to the electrical conductor 46 through the winding of a relay 53. An electrical conductor 54 also connects the electrical conductor 46 to a field effect transistor. The relay 53 includes a normally open switch 55 which is interposed in current controlling relation with respect to electrical conductor 42. The relay 53 is also mechanically connected to switch 51 to simultaneously operate switch 51 with switch 55.

During operation of the clock 10, the time constant condenser 48 will be alternately cycled through its leak down on discharging phase and its charging phase. After the time has been charged, a negative charge will buildup at the contact 50a of the field effect transistor 50. As long as the field effect transistor is subjected to a negative bias at contacts or gate 50a, then current will not flow from conductor 54 to conductor 52 and thereby close a potential across relay winding 53. As the current (holding bias) leaks down from the time constant condenser 48 and from the gate 50a through the resistor 49, the negative bias at 50a progressively decreases until there is no negative bias at 50a and current will then flow from conductor 54 through the field effect transistor to conductor 52. This shuts the current across the relay field (conductors 52 and 54) and resistor 60. When this occurs, the relay switch circuit is closed and completes the pulse circuit to the battery 44 through conductor 41 to the trip coil 39. It is pointed out that switches 51 and 55 are closed when the relay circuit is energized.

When the trip coil 43 is energized, the peripheral element 31 of the outer magnetic member 19 which is positioned between the poles of the electro-magnet 38 will be shifted in a clockwise direction, as viewed in FIG. 3, because of the interaction of the magnetic forces of the electro-magnets and the outer magnetic member. In this respect, it will be seen that the peripheral element 31 positioned between the poles of the electro-magnet will be urged in a clockwise direction by the combined attractive and repulsive forces of the electro-magnet acting on the peripheral element. The

next adjacent peripheral element will be urged in a clockwise direction and the repulsive force exerted by the pole of the electro-magnet closest adjacent the moving peripheral element will further urge the peripheral element in a clockwise direction. Since the trip coil is energized by an electrical impulse of momentary duration, the electro-magnet will be energized only for a time sufficient to shift the outer magnetic member through an arc so the next adjacent peripheral element is positioned between the poles of the electro-magnet.

As pointed out above, the switch 55 will be closed and the seitch 51 will be shifted to energize a trip coil 39 by a momentary impulse and the relay will then be de-energized. When the tripping circuit is de-energized, the switch 55 will be opened and the seitch 51 will be shifted to the position illustrated in FIG. 4 to begin again the condenser discharging phase. The duration of the discharging phase is five minutes to that the pulse unit generates an electrical impulse to energize the coil 39 at 5 minute intervals. With this arrangement, the outer magnetic member is shifted relative to the face or dial of the clock at 5 minute intervals. The outer magnetic member with the minute hand attached thereto also revolves relation to the inner magnetic member until the outer magnetic member has revolved through an arc of 360°.

When the outer magnetic member 19 has revolved through an arc of 360°, means are provided which will be actuated to interlock the outer magnetic member with the inner magnetic member so that the magnetic members will move together through the next increment of movement. To this end, the outer magnetic member 19 is provided with a pair of shiftable locking elements 56 formed of magnetic material and which are spaced apart a distance corresponding to a distance only slightly greater than the width dimension of one of the peripheral elements on the inner magnetic member 23. These locking elements 56 are positioned adjacent 35 and rearwardly of the peripheral element on the magnetic member which is disposed in the same vertical plane as the minute hand.

Thus when the minute hand is moved to the number twelve on the dial which also corresponds to the position of the electro-magnet 38, the element 56 will shift vertically downwardly through a slot 57 in the supporting wall 13a when the electro-magnet is energized and will engage the peripheral element on the inner magnetic member 23. Thus when the outer magnetic member is then moved through its arc of 30° with minute hand on 12, the inner magnetic member will be revolved accordingly. The locking elements 56 will then be retracted since the electro-magnet 38 will be de-energized, the outer magnetic member will also have revolved to physically position the locking elements a sufficient distance away from force of the electro-magnet. It will therefore be seen that the hour hand will be shifted after the outer magnetic member is moved through an arc of 360° which requires a time duration of one hour.

It is also pointed out that a frequency divider unit may be used advantageously with the magnetic clock to increase the accuracy thereof. The frequency divider units (not shown) but which are commercially available, divides the normal 60 cycles per second frequency into one cycle per second thus rendering the magnetic clock extremely accurate over a year's span.

From the foregoing description, it will be seen that I have provided a novel magnetic clock which is not only of simple and inexpensive construction, but one which functions in a more efficient manner than heretofore known comparable clocks.

What is claimed is:

1. A clock comprising
a first revolvable magnetic member of circular cross
sectional configuration and having a plurality of
circumferentially spaced apart peripheral elements 10
integral therewith and projecting radially out-
wardly therefrom,
an hour hand affixed to said first magnetic member
and projecting radially therefrom,
a revolvable second magnetic member of circular 15
cross-sectional configuration and positioned con-
centrically exteriorly of said first magnetic mem-
ber, a plurality of circumferentially spaced apart
peripheral elements integral with said second mag-
netic member and projecting radially therefrom, a 20
minute hand connected with said second magnetic
member and projecting radially therefrom,
a stationary magnetic bearing of circular cross-
sectional configuration and disposed concentri-
cally between said first and second magnetic mem-
bers and exerting a repulsive force respectively on
said first and second magnetic members,
magnetic holding means positioned closely adjacent
the peripheral elements on said first magnetic
member, said holding means and said last men-
tioned peripheral elements exerting an attractive
force on one another for normally holding the first

magnetic member against movement,
electro-magnetic means positioned closely adjacent
the peripheral elements on said second magnetic
member and when energized causing said second
magnetic member to revolve through a predeter-
mined arc of approximately 30°,
electrical pulse means connected with said electro-
magnetic means and being operable to energize
said electro-magnetic means with a momentary
electrical impulse whereby said second magnetic
member will be moved through said predetermined
arc relative to said first magnetic member,
and releasable locking means on said second mag-
netic member shiftable in response to movement of
said second magnetic member through an arc of
360° relative to said first magnetic member, said
locking means releasably engaging said first mag-
netic member to shift the same with said second re-
volvable member through said predetermined arc
and then being shiftable out of engagement with
said first magnetic member.

2. The clock as defined in claim 1 and magnetic hold-
ing means positioned closely adjacent the peripheral
elements on said second magnetic member, said last
mentioned holding means and said last mentioned per-
ipheral elements exerting an attractive force on one
another for normally holding the second magnetic
member against movement.

3. The clock as defined in claim 1 wherein said each
of said magnetic members and said bearing are of hour
glass configuration.
